UNITED STATES PATENT OFFICE.

CECIL C. CHADWICK, OF NEWTON, MASSACHUSETTS.

BUBBLER FOUNTAIN.

Application filed August 24, 1920. Serial No. 405,567.

To all whom it may concern:

Be it known that I, CECIL C. CHADWICK, a citizen of the United States, and resident of Newton, county of Middlesex, State of Massachusetts, have invented an Improvement in Bubbler Fountains, of which the following description, in connection with the accompanying drawing, is a specification, like characters on the drawing representing

10 like parts.

This invention relates to bubbler fountains, and has for its object to provide an improved bubbler which is simple in its construction and inexpensive to manufacture, 15 which is provided with a perfectly smooth exterior surface so that it can be easily kept clean, which is constructed so that it can be readily adjusted for different pressures, and which has other features of improvement, 20 all as will be more fully hereinafter set forth.

In order to give an understanding of my invention, I have illustrated in the drawings a selected embodiment thereof which will now be described, after which the novel features 25 will be pointed out in the appended claims.

Fig. 1 is a side view of a bubbler embodying my invention:

Fig. 2 is a vertical sectional view;

Fig. 3 is a bottom plan view;

Fig. 4 is a section on the line 4—4, Fig. 2.

My improved bubbler comprises a head portion 1 and a neck portion 2, the latter being constructed to be screw-threaded to a 35 pipe in usual manner. The head portion 1 is provided with the interior chamber 3 and with the discharge port 4. The neck 2 is hollow and is interiorly screw-threaded. Situated within the neck 2 are two plugs 40 5 and 6 each of which preferably has screw-threaded engagement with the neck. The plug 5 is provided with a central duct 7 and the plug 6 is provided with a plurality of ducts 8 which are out of line with the duct

45 7. This plug 6 is also provided with a screw-driver slot 9 in its upper face, and the discharge opening 4 is of sufficient size to permit a screw-driver to be inserted therethrough for the purpose of adjusting the plug 6. The purpose of these plugs is to regulate the flow of water through the bubbler according to the pressure in the water system to which the bubbler is attached.

The two plugs will be adjusted so as to leave 55 a space between them, the extent of this

space depending upon the pressure of the water. If the water pressure is high the plug 6 will be screwed down closer to the plug 5 than if the water pressure is relatively low. The space between the plugs 5 and 6 constitutes a pressure-regulating space which regulates the pressure at which the water is delivered through the ducts 8 and thus regulates the height to which the water will rise as it issues from the discharge 65 opening 4. It will be noted that there are a plurality of ducts 8 in the plug 6 and a single duct 7 in the plug 5. The total cross-sectional area of the ducts 8 is greater than that of the duct 7 and, therefore, the water 70 has a freer flow from the chamber between the plugs than it has into the chamber. The result of the freer discharge from this chamber is that the pressure in the chamber will be appreciably reduced below that in the inlet pipe, and this pressure is still further reduced in the chamber 3 because the discharge opening 4 has a greater cross-sectional area than the discharge from the chamber between the plugs. The head 1 is provided 75 with the inwardly directed flange 10 surrounding the discharge aperture 4, thereby making a discharge aperture of considerable length. The purpose of this is to give the stream a definite direction as it is delivered 80 from the bubbler, thereby making it more easy to drink from. The head 1 is provided with waste ports 11 leading from the chamber 3, and through which said chamber may be drained.

In use, the water from the water system will pass through the duct 7 under high pressure into the space between the ducts and will then flow through the ducts 8 into the chamber 3. The velocity with which it flows 95 into the chamber 3 will depend something on the relative adjustment of the plugs 5 and 6, and it is the intention that these should be so adjusted that when the chamber 3 is filled, the pressure will force the water out through the discharge opening 4 in a stream which will rise a short distance above the top of the head. Owing to the presence of the flange 10 which makes an elongated discharge opening 4, the stream which is delivered from the bubbler will always assume 100 a certain direction, thus making it easier to drink from the bubbler.

The plug 6 can be readily adjusted from the exterior of the head and therefore the 110

bubbler can be adjusted for any pressure while it is attached to the system, and by simply inserting a screw-driver through the opening 4 and turning the plug 6 in one direction or the other.

- It sometimes happens that mischievous persons will insert a pencil or other obstruction into the discharge opening of the bubbler for the purpose of increasing the pressure in the chamber 3, thus causing a small stream of water to be thrown from the bubbler a considerable distance. In order to avoid anything of this sort, I propose to make the waste openings 11 of sufficient cross sectional area so that if the discharge opening 4 is closed or partially closed, the water in the chamber 3 can flow out of the waste openings at a sufficiently rapid rate to prevent an undue pressure from building up in the chamber 3. These waste openings or vent ports, however, are not sufficiently large to interfere with the ordinary use of the bubbler when the discharge 4 is unobstructed.
- 25 The plug 6 not only constitutes a regulating plug, but it also constitutes a valve, for by screwing said plug hard down against the plug 5 the water will be completely shut off.
- 30 It will be noted that the exterior surface of the head 1 is perfectly smooth and free from indentations, recesses or grooves. This is a decided advantage because it facilitates the cleaning of the bubbler and dispenses with any hollows or recesses in which dirt or filth may collect.

I claim:

1. A bubbler having a chambered head and a hollow neck portion, said head having a discharge opening, two plugs screw-threaded into the neck portion and adjustable relative to each other, both plugs having apertures therethrough out of alignment with each other and the outer plug having apertures giving a greater total cross-sectional area than those of the inner plug.

2. A bubbler having a chambered head and a hollow neck portion, said head having a discharge opening, a plug screw-threaded into the lower end of the neck and provided with a central duct, a regulating plug screw-threaded into the neck above the first-named plug and spaced therefrom, said regulating plug being provided with a plurality of ducts out of line with the central duct and having a total cross-sectional area greater than that of the central duct.

3. A bubbler comprising a head portion and neck portion, said head portion having a smooth exterior surface free from indentations, and also having an exterior chamber and a discharge opening, said neck portion being hollow, and two plugs screw-threaded into the neck portion but spaced from each other, both plugs having ducts therethrough, the ducts through the outer plug having a total cross-sectional area greater than those through the inner plug.

In testimony whereof, I have signed my name to this specification.

CECIL C. CHADWICK
